HYDRAULIC CYCLE CONTROL

Louis C. Huck, Buchanan, Mich., assignor to Hux-
on Holding Corporation, a corporation of Mich-
igan

Application July 24, 1936, Serial No. 92,342

10 Claims. (Cl. 121—45)

This invention relates to reciprocating fluid pressure motors of the type utilized to operate machine tools and the like and it resides in an improvement over the fluid pressure motor control means disclosed in the co-pending application of Ralph A. Miller and Will E. Morris, Serial No. 92,362, filed July 24, 1936.

In the aforementioned application of Ralph A. Miller and Will E. Morris there is disclosed an automatic valve control means for reversing the fluid pressure connections to an operating cylinder upon completion of the movement of a piston in said cylinder in one direction. This means resides in a reversing valve actuator which is responsive to the drop in exhaust pressure at one side of the operating piston incident to the completion of the exhaust movement of that piston when it strikes the end wall of the cylinder. The advantage of such a means resides in the fact that it reverses the operating cylinder at exactly the same point in its path of movement during each cycle, namely, after it has struck the end wall of the cylinder. This results in a very accurate limitation of the travel of the operating system and associated machine tool or work holder.

It has been found that while the structure disclosed by Miller and Morris is operative for its intended purpose, there is a slight lag between the completion of the operating piston movement and the reversal of the fluid pressure connection to the operating cylinder, which has the effect of slowing the cycle of operation of the machine. This time lag is due to the fact that the valve actuating cylinder exhausts through that end of the main operating cylinder which exhausts during the working stroke, which end in turn exhausts through a relatively restricted outlet. Thus, the exhaust or back pressure in the actuating cylinder has a tendency to retard its movement in the direction in which it shifts the reversing valve to reverse the operating cylinder. The present invention is broadly directed to the provision of means for quickly venting that side of the actuating cylinder which exhausts during the working stroke as soon as the working stroke is completed.

A more specific object of the invention is to provide a one way conduit between one end of the operating cylinder and one end of the actuating cylinder, which conduit has provided therein means for automatically venting the actuating cylinder to the storage reservoir when the exhaust pressure drops in that end of the

operating cylinder which exhausts during the working stroke.

Other objects and advantages of the invention will become apparent from the accompanying drawing and attached specification and 5 claims.

The drawing illustrates, partly diagrammatically, a preferred form of the invention, the essential elements thereof being illustrated in section.

In the drawing there is shown at 1 the cylinder of a hydraulic motor which includes a piston 2 and piston rod 3. The piston rod 3 may be adjustably connected to a reciprocating work or tool holder, not shown, of a machine tool. Such 15 a machine may, for example, be a drill press having a reciprocating drill head which is adjustably connected to the piston rod.

The cylinder 1 has a removable head 4 secured in place by suitable studs 5. The opposite 20 end of the cylinder is formed at 6 to receive a conventional packing gland 7 having a packing 8 for preventing leakage around the piston rod. The interior end wall 9 is flat and is adapted to engage abutment 10 on the piston when the 25 latter reaches the limit of its movement in the working direction. A similar abutment 11 is provided at the opposite face of the piston, and piston rings 12 are fitted into conventional ring grooves about the periphery of the piston. The 30 walls of the cylinder adjacent its lower end are provided with a pair of ports 13 and 14, while similar ports 15 and 16 are provided adjacent the opposite end of the cylinder. These ports are threaded or otherwise adapted to receive 35 suitable fluid conduits 17, 18, 19 and 20, respectively.

Each of the conduits 17 and 19 is adapted to operate either as a pressure or exhaust conduit for the end of the cylinder to which it is connected and these functions are controlled by a reversing valve, indicated generally at 21, which is interposed in lines 17 and 19. The reversing valve comprises a casing 22 closed at one end and having at the opposite end thereof a removable 45 closure plate 23 secured in place by studs 24. Plate 23 is provided with an opening for the reception of a packing gland 25 and a valve rod 26 extends through the opening and has a valve head 27 on its inner end. The valve housing 50 22 is provided with five ports 28, 29, 30, 31 and 32 spaced respectively along the axis of the housing and the conduits 17 and 19 are threaded or otherwise secured into the ports 28 and 29, respectively. Port 30 communicates with a con- 55

duit 33 which is connected to the discharge side of a pump 34, while ports 31 and 32 communicate through conduits 35 and 36 with a low pressure storage reservoir 37. The intake of pump 34 is connected to reservoir 37 by a conduit 38.

A valve operating lever 39 is slotted at its end 40 to receive the end of valve rod 26 and the end of the valve rod is threaded to receive a pair of nuts 41 and 42 which are adapted to engage opposite sides of the end of the lever. The lever 39 is pivoted at 43 to a fixed portion of the machine 44, and carries an extension 45 to which is secured a roller 46. A cam 47 adjustably secured to the piston rod 3 of the hydraulic motor by any suitable means, such as set screws 48, has a bevel 49 adapted to cooperate with the roller. It will be apparent that as piston 2 approaches the upper end of cylinder 1, as viewed in the drawing, the beveled portion 49 of cam 47 can engage roller 46 and will shift lever 39 to the position it assumes in the drawing. However, upon return movement of the piston, downward as viewed in the drawing, cam 47 will pass beyond roller 46 without changing the position of lever 39.

The lever 39 is apertured at 50 to receive a piston rod 51 of an actuating motor comprising a cylinder 52 and a piston 53 having abutments similar to those on piston 2. This cylinder has a removable closure plate 54 at one end thereof, held in place by studs 55, and at the opposite end is provided with a packing gland 56 for the reception of piston rod 51. The upper end of cylinder 52 is in constant communication with the upper end of the operating cylinder 1 through conduit 20. At its upper end, the rod 51 has a reduced portion 57, and a compressible abutment member is mounted on the latter and includes a pair of telescopic housings 58 and 59 and a coiled compression spring 60 within the housings. A nut 61 threaded on the end of rod 57 is provided for retaining this assembly in place. It will be observed that when piston 53 moves downwardly as shown in the drawing, housing member 59 will engage one side of lever 39 and will resiliently force it in a clockwise direction about pivot 43.

The motor 52, 53, etc., it will be observed, is of the double acting expansible chamber type inasmuch as movement of the piston is accompanied by an increase in the volume of the space at one end of the cylinder and a reduction of the volume at the opposite end.

The opposite, or lower, end of cylinder 52 is in communication with the lower end of cylinder 1 through conduit 62, a one-way dump valve mechanism indicated generally at 63, and a conduit 18. The one-way dump valve mechanism 63 comprises a housing 64 containing a pair of parallel longitudinal bores 65 and 66 extending throughout its length. Longitudinal bores 65 and 66 are connected adjacent their ends by a pair of transverse bores 67 and 68, each of which is drilled from one side of housing 64 through both longitudinal bores. The open ends of bores 67 and 68 are closed by plugs 69 and 70, respectively. A third transverse bore 71 extends from the exterior of housing 64 into communication with the longitudinal bore 65 and is connected by means of an adapter 72 to a conduit 73 extending to the reservoir 37.

A valve housing 74 is fitted into bore 65 and is held in place against an abutment 75 by a plug member 76 which is threaded into one end 75 of longitudinal bore 65. Housing 74 is provided

with a cylindrical recess 77 for the reception of a sliding valve member 78. A longitudinal passageway 79, which connects recess 77 with the right hand end of the housing, is adapted to be closed by a projection 80 on valve member 78 when the latter assumes the position shown in the drawing. The valve housing 74 contains a plurality of radially extending transverse bores 81, communicating with an annular groove which in turn communicates with the transverse bore 10 71 in housing 64. When valve member 78 is shifted to the left from the position shown in the drawing, a communication is provided from transverse bore 71 through recess 77 to passageway 79 and thence into bore 65. Valve member 15 78 is provided with a small longitudinal groove 108 and a communicating circumferential groove 109 through which any fluid that may leak past the seal of projection 80 may flow to the exhaust passages 81. This prevents the pressure from 20 building up over the entire area of the right hand end of member 78 and perhaps prematurely opening the valve.

The plug member 76 is provided with a longitudinal bore 82, to the outer end of which the 25 conduit 18 is connected by means of an adapter 83. This bore at its inner end communicates with a transverse bore 84 which is aligned with the bore 67 in the housing 64, and at the inner end of the plug 76, a recess 85 is in communication with the transverse bore 84 by means of passages 86. At its right end the bore 65 is connected to the conduit 62 by means of a threaded adapter 87.

One end of longitudinal bore 66 is closed by 35 plug 88 while the other is threaded for the reception of the ball and spring supporting member 89 of a one-way valve assembly. This one-way valve comprises a seat member 90 having an axial bore 91, which is seated against a shoulder 92 formed by an enlargement of bore 66. The ball and spring supporting member 89 is axially bored for the reception of a spring 93, which operates to hold a ball valve 94 against the seat 90, and prevent flow of fluid from the 40 transverse bore 68 into bore 66 beyond the seat 90. Flow in the opposite direction is permitted by reason of the compressibility of the spring, and a slot 95 in the side of member 89 adjacent the seat. A cap 96 is threaded on the end of 50 the member 89 and engages the face of the housing 64 to lock the member 89 in position. Suitable packing, as indicated at 97, is provided between the cap 96 and housing 64.

By reason of the construction illustrated and 55 described, fluid may flow from conduit 18 through passages 82, 84, 67, 66, 91, past the one-way ball valve, through bores 68, 65 and thence to conduit 62, but flow in the opposite direction is prevented by ball 94. Moreover, if at any time the pressure in conduit 62 exceeds that in 18 by a predetermined amount, valve member 78 will be moved off its seat, opening communication between bores 79 and 71 and thus permitting the flow of fluid from conduit 62 through the valve housing 65 74, transverse bore 71 and conduit 73 to the reservoir 37. This arises by reason of the fact that the pressure in conduit 18 is communicated to the recess 85 at the end of plug 76 and thus is effective against one end of valve 78, while the pressure in conduit 62 is communicated through bores 65 and 79 to the extension 80 on valve member 78. It is apparent that inasmuch as the effective areas at the opposite sides of valve 78 when the latter is closed are different, that no motion of 75

this member will occur until the pressure in conduit 62 exceeds that in conduit 18 by a predetermined amount, whereupon the valve member will be initially cracked. Immediately thereafter the pressure from conduit 62 will be effective over the entire area of the lower end of valve member 78, and the valve will open rapidly and remain open to vent conduit 62 to the reservoir 37.

An important feature of this valve mechanism resides in the fact that valve 78 will open automatically as soon as the exhaust pressure at the lower end of cylinder 1 drops a predetermined amount. This arises by reason of the fact that the pressure trapped in the lower end of the actuator cylinder by ball valve 94 is effective on the reduced end 80 of valve member 78. Thus, as soon as the exhaust pressure, and therefore the pressure on the opposite end of valve 78, drops below normal, the valve member will be opened to vent cylinder 52.

Between the cylinder 1 and the reversing valve 21 and interposed in conduit 17, a one-way throttle valve 98 is provided which comprises a block 99 having a longitudinal bore 100 passing entirely therethrough. The opposite ends of bore 100 are connected respectively to the adjacent ends of conduit 17, and an adjustable metering screw 101 is provided for restricting the flow through this bore. In order to permit a free flow of fluid to the cylinder 1 through conduit 17, a one-way by-pass is provided around the screw 101 and comprises connected passages 102, 103 and 104, and a one-way ball valve. The latter comprises a ball 105 at the end of passage 103 and a spring 106 engaging the ball and which is mounted in a housing 107 secured to block 99. The outer end of bores 102 and 104 may be closed by any suitable means, such as plugs.

The drawing shows the parts in the position they occupy during downward movement of the operating piston 2, towards its piston rod, and before the completion of such movement. Under this condition the reversing valve 27 will connect the pump 34 to the upper end of cylinder 1 through conduit 33, the housing of the reversing valve, and conduit 19, thus supplying pressure to effect movement of the piston. At the same time the lower end of cylinder 1 will be exhausting through conduit 17, the throttle valve 98, the lower end of housing 22 of the reversing valve, conduit 35 and conduit 36 to the reservoir 37. The metering screw 101 will be adjusted to provide an appreciable back pressure at the exhaust side of piston 2 for a purpose to be described.

The high pressure at the upper side of piston 2 will be communicated through conduit 20 to the piston rod end of cylinder 52 of the reversing valve actuator. At the same time the pressure in the lower end of cylinder 52 cannot be much less than the exhaust pressure in the lower end of cylinder 1 because any appreciable difference in pressure will lift ball valve 94 and permit the fluid in the lower end of cylinder 1 to flow through conduit 18, bores or passageways 82, 84 67, 66, 91, 68 and through the right hand end of bore 65 to the lower end of cylinder 52 through conduit 62. Spring 93 is relatively light with the result that a small pressure differential will lift it off its seat.

It is thus apparent that full operating pressure is effective upon the upper end of the valve actuating piston 53, while a pressure at least not appreciably less than normal exhaust pressure for the lower end of cylinder 1 is effective upon the opposite end thereof. The proportions of the

parts and the operating and exhaust pressures are so selected, however, that the low pressure at the lower end of piston 53 will overcome the high pressure at the opposite end and maintain the piston 53 at the rod end of the cylinder, as shown in the drawing. This overbalancing of a high pressure by a lower pressure is effected by reason of the fact that the piston rod 51 reduces the effective area at the upper end of piston 53 sufficiently to compensate for the excess pressure at that end. The relative diameters of the piston and the piston rod of the actuator may be so proportioned as to insure that the piston 53 will remain at its uppermost position until the resistance to movement of piston 2 exceeds the maximum resistance that will be offered by the tool during normal use.

Other features which contribute to effect this balance between unequal pressures should be noted. In the first place the working pressure in the cylinder 1 is applied at the upper or rodless side of the piston 2 with the result that for a given resistance to movement of piston 2, the difference between the working and exhaust pressures will be less, due to the decreased area at the exhaust side, than would be possible if the areas were the same. This means either that the working pressure and therefore the pressure in the upper end of actuator cylinder may be less or that the exhaust pressure in the lower end of cylinder 1 may be greater than would otherwise be possible. In either case, this reduction in the pressure differential makes it easier to hold the piston in actuator cylinder 52 in its upper position.

The piston 53 will be held in its uppermost position so long as piston 2 continues its movement toward the lower end of cylinder 1. However, when piston 2 reaches and abuts the end of its cylinder, no further movement is possible regardless of the pressure at the upper end of the cylinder. Therefore, the fluid at the exhaust side will be relieved of the normal exhaust pressure caused by movement of the piston. As soon as the pressure at the lower end of cylinder 1 drops below the normal exhaust pressure, the pressure in conduit 18 and chamber 85 will likewise drop, and the normal exhaust pressure which is trapped at the lower end of cylinder 52 by ball valve 94, and which acts on the reduced end 80 of vent valve 78, will shift valve member 78 and vent the lower end of cylinder 52 to reservoir 37 through conduit 73. As previously described, this permits a rapid exhaust of the fluid at the lower end of the actuator cylinder 53 through conduit 62, the right hand end of bore 65, bores 79, 81, 71 and conduit 73 to the reservoir 37. In this way the actuator piston 53 will rapidly move downwardly under the influence of full operating pressure from the upper end of cylinder 1 through conduit 20, bringing the resilient abutment member 59 into contact with the lever 39 and swinging the latter clockwise to shift reversing valve 27 downwardly.

Shifting of the reversing valve from the position illustrated, places conduit 17 in communication with the pump through conduit 33 and the valve housing, and it places conduit 19 in communication with the discharge reservoir 37 through conduit 36 and the valve housing. The pressure in conduit 17 passes through the by-pass passages and one-way valve of the metering device 98 to the lower end of cylinder 1, thus initiating and effecting movement of the operating piston 2 in a reverse direction, or upwardly

as viewed in the drawing. During such movement the fluid at the upper end of piston 2 discharges freely through conduit 19.

During the reverse movement of piston 2, the high pressure at the lower end of cylinder 1 is communicated through port 14, conduit 18, the one-way dump valve mechanism 63, and conduit 62 to the lower end of the actuator piston 53. Since free exhaust pressure is effective upon the upper end of piston 53, this piston will move upwardly until it assumes the position shown in the drawing. Such motion, however, will not affect the position of lever 39, which will remain in the position to which it was previously moved by the reverse movement of the actuator piston 53, until roller 46 is engaged by the beveled surface 49 of cam 47 on piston rod 3. During the upward movement of piston 2, valve member 78 in the one-way dump valve mechanism will be restored to the position shown in the drawing by reason of the excess pressure in conduit 18 over that in conduit 62. This excess in pressure exists by reason of the pressure drop between these two conduits due to the flow of fluid from conduit 18 through the bores 67, 66, 92 and 68, and also by reason of the resistance of spring pressed ball 94.

Near the end of the upward movement of piston 2 the beveled surface 49 of cam 47 engages roller 46 on lever 39 and thereafter shifts the lever and reversing valve to the position shown in the drawing. From this point the above described cycle of movement will be repeated.

It will be apparent from the description and the accompanying drawing that the invention constitutes an improved means for reversing a reciprocating fluid pressure motor at a fixed point in its stroke, and only after its movable element has engaged and been stopped by a fixed abutment. The invention not only positively insures that the movable carriage or other device operated by the motor will always change its direction of motion at exactly the same point in each cycle, but provides a quick reversal of the carriage at that point. This feature is of great value where very accurate cuts must be made by production machine tools.

While there is illustrated and described the preferred form of the invention, it is apparent that considerable variations may be made in the details and arrangement of parts without departing from the spirit thereof, or the scope of the appended claims.

What is claimed is:

- 55 1. Means for reversing a fluid pressure motor having intake and exhaust passages comprising a reversing valve for controlling said passages, a pressure responsive means for operating said reversing valve, means for conducting fluid from one side of said motor to said pressure responsive means, an exhaust passage for said pressure responsive means independent of said motor intake and exhaust passages, means operable upon a predetermined decrease in the pressure in said side of the motor for exhausting the pressure from said pressure responsive means through said independent exhaust passage, and means for operating said pressure responsive means upon exhaust of fluid therefrom through said independent exhaust passage.
- 60 2. Means for reversing a reciprocating fluid pressure motor comprising a reversing valve, a pressure responsive means for operating said reversing valve, an exhaust valve for said pressure responsive means, means including a one-way

value for conducting fluid from one side of said motor to said pressure responsive means, means associated with said exhaust valve for opening the same upon a predetermined decrease in the pressure in said one side of the motor, and means for operating said pressure responsive means upon exhaust of fluid therefrom through said exhaust valve.

3. Means for reversing a reciprocating fluid pressure motor comprising a reversing valve, a pressure responsive means for operating said reversing valve, an exhaust valve for said pressure responsive means, means including a one-way value for conducting fluid from one side of said motor to said pressure responsive means, means associated with said exhaust valve operable upon a flow of fluid from the motor to said pressure responsive means to close said valve and operable when the pressure in said side of the motor is less than that in said pressure responsive means by a predetermined amount to open the valve, and means for operating said pressure responsive means upon exhaust of fluid therefrom through said exhaust valve.

4. In combination, a fluid pressure motor including a piston and cylinder, means including a reversing valve for reversing pressure and exhaust connections to the opposite ends of said cylinder, an expansible chamber actuator for operating said reversing valve, conduit means connecting one end of said cylinder to said expansible chamber, means tending to operate said expansible chamber actuator to collapse the chamber and thereby shift the reversing valve, said means being ineffective to overcome the normal pressure in said chamber but effective when said pressure is reduced below normal, and a dump valve for venting said chamber when the exhaust pressure in said one end of the cylinder drops below normal.

5. In combination, a fluid pressure motor comprising a piston and cylinder, means including a reversing valve for reversing pressure and exhaust connections to the opposite ends of said cylinder, an expansible chamber actuator for operating said reversing valve, conduit means connecting one end of said cylinder to said expansible chamber whereby the pressure is substantially equalized in said end of the cylinder and said chamber, adjustable means for restricting the exhaust outlet for said end of the cylinder, means tending to operate said expansible chamber actuator to collapse the chamber and thereby shift the reversing valve, said means being ineffective to overcome normal exhaust pressure in said chamber but effective when said exhaust pressure is reduced below normal, and a dump valve for venting said chamber when the pressure in said chamber exceeds that in said end of the motor cylinder.

6. In combination with a double acting fluid pressure motor including a piston, a cylinder and a reversing valve for reversing the pressure and exhaust connections at opposite ends of said cylinder, of means operatively connected to said reversing valve including a second fluid pressure motor having a piston and cylinder, a piston rod on said second piston, an open conduit connecting one end of said first cylinder with the piston rod end of said second cylinder, means connecting the opposite ends of said cylinders and adapted to permit passage of fluid in one direction only from said first to said second cylinders, the cross-sectional areas of the second piston and its rod being so proportioned that the normal operative

pressure at said piston rod end of the second cylinder is insufficient to overcome the normal exhaust pressure at the opposite end of said second cylinder, and means operable when the exhaust pressure in said opposite end of the first motor falls below normal for exhausting fluid from said opposite end of the second motor.

7. In combination with a double acting fluid pressure motor including a piston, a cylinder and a reversing valve for reversing the pressure and exhaust connections at opposite ends of said cylinder, means operatively connected to said reversing valve including a second fluid pressure motor having a piston and cylinder, a piston rod in said second cylinder, an open conduit connecting one end of said first cylinder with the piston rod end of said second cylinder, means connecting the opposite ends of said cylinders and adapted to permit passage of fluid in one direction only from said first to said second cylinder, the cross-sectional areas of the second piston and its rod being so proportioned that the normal operative pressure at said piston rod end of the second cylinder is insufficient to overcome the normal exhaust pressure at the opposite end of said second cylinder, means for venting the said opposite end of the second cylinder when the exhaust pressure at said opposite end of the first cylinder drops below normal, a lost motion device in the connection between said second motor and said reversing valve for preventing operation of the valve by said second motor when said second piston moves toward the piston rod end of said second motor but permitting operation in the opposite direction, and means associated with the first motor for shifting the reversing valve in the direction in which it cannot be moved by said second motor when the piston of said first motor approaches the end of its travel in the direction toward said open conduit.

8. The combination with a reciprocating double acting fluid pressure motor comprising a cylinder, a piston, a piston rod extending through one end of the cylinder, and a reversing valve, of a second cylinder, a piston in said second cylinder, a piston rod connected to said second piston, extending through one end of said cylinder and connected to said reversing valve, fluid conduit means connecting the rodless end of the first cylinder with the rod end of the second cylinder, fluid conduit means connecting the rod

end of the first cylinder with the rodless end of the second cylinder, a one-way valve in said last named fluid conduit means adapted to prevent flow of fluid from the second cylinder to the first, and means automatically operable when the pressure in the rod end of the first cylinder is decreased to a predetermined ratio with respect to the pressure in the rodless end of the second cylinder to open an exhaust passage for the fluid in the rodless end of the second cylinder, said means being operable to close the exhaust passage when the pressure in the rod end of the first cylinder exceeds that in the rodless end of the second cylinder.

9. Means for reversing a reciprocating fluid pressure motor having intake and exhaust passages comprising a reversing valve for controlling said passages, means for operating said reversing valve including a second fluid pressure motor having an expansible chamber, and means for exerting a force on said second fluid pressure motor tending to collapse said chamber and thereby shift said reversing valve, means for conducting exhaust fluid from one end of said first motor to said chamber to oppose the action of said means tending to collapse the chamber, and means operable upon a drop in the exhaust pressure at said one end of said first motor for venting said chamber.

10. Means for reversing a reciprocating fluid pressure motor having intake and exhaust passages comprising a reversing valve for controlling said passages, an expansible chamber fluid pressure motor for operating said reversing valve, means for exerting a force on said second motor tending to collapse the chamber thereof and thereby operate said reversing valve, means for conducting fluid from one end of said first motor to the expansible chamber on said second motor, means for maintaining sufficient exhaust back pressure on said one end of said first motor when said motor is exhausting at said one end to maintain sufficient pressure in said chamber to overcome the collapsing force of said first means and thereby maintain said chamber in expanded condition, an independent exhaust passage for said chamber, an exhaust valve for controlling said passage, and means operable upon a drop in said exhaust back pressure for opening said exhaust valve.

LOUIS C. HUCK. 50
